UNITED STATES PATENT OFFICE.

STANLEY A. DUVALL, OF ELKHART, INDIANA.

TELEPHONE-TRANSMITTER.

No. 833,449.

Specification of Letters Patent.

Patented Oct. 16, 1906.

Application filed March 5, 1903. Serial No. 146,310.

To all whom it may concern:

Be it known that I, STANLEY A. DUVALL, a citizen of the United States, residing at Elkhart, Indiana, have invented a certain new and useful Improvement in Telephone-Transmitters, of which the following is a specification.

My invention relates to microphone or battery transmitters of the granular type, and has for its object the production of an instrument of this kind which shall be sensitive but certain in its action, which can be readily adjusted at all times without dismantling, and which will retain its adjustment under trying conditions and with severe usage. To this end I adopt the principles and embody them in a manner which will presently be described, and pointed out in the appended claims.

My invention comprises an arrangement wherein the microphone-button is made as a complete unit, thus gaining all the advantages of the solid-back instrument, but is provided with an adjustment for the electrodes which obviates the necessity for absolute uniformity in the parts or their assembling, thus doing away with the expert labor and producing an article of a purely commercial type. In this arrangement instead of a mica auxiliary diaphragm I employ a diaphragm of metal, preferably refined aluminium, which after repeated experiments I find gives a better results for my purposes than any other metal that is commercially available. The only material heretofore used in this manner has been mica, and while by expert selection sheets of this material of fairly uniform thickness can be obtained it is impossible to get perfect uniformity in the physical properties. Moreover, slight variations in thickness seem to produce quite a difference in the tone of the instrument, so that it is necessary to discard much material to obtain the little that is of use. On the other hand, in aluminium I have a material that presents two striking advantages for this purpose—lightness of mass to be moved and perfect and uniform resilience. I commonly employ cold-rolled sheet-aluminium one-thousandth of an inch thick to micrometer gage. Being of metal, the diaphragm is impervious to moisture, is not injured by changes in temperature, and gives very uniform results in use. Owing to its lightness, as well as its small diameter and mass, it has a very high natural period en-

tirely removed from the ordinary range of 55 voice vibrations, which, therefore, it does not alter, but reproduces with great fidelity.

My invention is illustrated in the accompanying drawings, wherein—

Figure 1 is a cross-section taken along the 60 middle line of the bridge of a transmitter embodying my improvements, while Fig. 2 is a detail view of the parts of the transmitter-button separated from each other.

Referring to Fig. 1, A is the front plate of 65 the transmitter, having a central opening *a* screw-threaded, as usual, for the reception of the hard-rubber mouthpiece *a'*. Extending around the circumference of the rear face of the front plate is the annular flange *a''*, 70 which has three functions. It forms a recess on the inside for the diaphragm to lie in, it forms a shoulder on the outside for the shell S to be screwed to, and it furnishes a face for the attachment of the bridge B. The dia- 75 phragm D has its edge surrounded by a soft-rubber gasket *d*, which insulates it from the front plate, and it is held in position by clamping and damping springs *d'*, all in the usual manner. The bridge B has a central 80 boss *b* and is provided with an axial opening *b'* for the reception of the stem of the button. The entire instrument when assembled and adjusted, so far as its operative parts are con- 85 cerned, is supported upon the front plate A and as a last step in the assembling is inclosed within the metal shell S, secured to the flange *a''* in any suitable manner. The shell has a flat base *s*, secured by screws *s'* or otherwise to the end of the hollow arm X, and is cen- 90 trally perforated, as at *s''*, to permit the passage of the circuit-wires from the diaphragm and the bridge connection, respectively, into the hollow arm, as shown.

The transmitter-button has for its essen- 95 tial parts the following, which are separately shown in Fig. 2 and assembled in Fig. 1: the metal cup or pill-box C, having a hollow stem *c* provided with internal screw-thread *c'* in the stem and external screw-thread *c''* on its front edge; rear electrode E, consisting of a metal disk *e*, with a carbon face *e'* and stem *e''* fitted to the hollow stem of the cup C and screw-threaded to work therein, being also provided with an end slot *e''* and lock-nuts *e'''*, 100 for the purpose of making and securing the adjustment; front electrode F', consisting of a metal disk *f*, with a carbon face *f'* and cen-

tral stem f^2 , screw-threaded to receive the lock-nuts f^3 , by which it is secured to the dia-
phragm D; aluminium auxiliary diaphragm G, secured to the back of the front electrode-
5 disk f by means of the screw-threaded disk-
nut g; interior ring bushing or lining H, which may be of rubber, compressed mica, or other suitable material and is fitted to the inside of the cup C, having a forward shoul-
10 der h, upon which the auxiliary diaphragm G rests; locking-ring c⁴, which, with an inter-
posed insulating-gasket h', holds down the auxiliary diaphragm upon the shoulder h and which is screwed to the cup C by means of its
15 threads c⁵ engaging with the threads c².

It will be observed that I make the front electrode smaller than the rear electrode in order to form the usual expansion-chamber for the granular carbon when it becomes
20 heated.

In assembling this instrument the steps are as follows: The microphonic "button," consisting of the cup C and the other parts shown in Fig. 2, is first assembled as a unit,
25 containing the proper quantity of granular material I. The diaphragm is then secured upon the front plate, and the stem f^2 of the front electrode is secured thereto by the nuts f^3 , the bridge B being at the same time
30 slipped over the stem c and screwed to the an-
nular flange a². The button is now adjusted roughly by means of the stem c, so that the auxiliary diaphragm G is under no tension, but is in a natural unbuckled condition,
35 when the stem c is rigidly secured by the set-
screw b². Up to this point no skilled labor is required, except that accuracy in assembling the button is somewhat necessary; but as this work is usually done by girls who are deft
40 with their fingers it is capable of swift and easy performance. The instrument being suitably connected up is finely and finally ad-
justed by means of a screw-driver inserted in the slot e³, this adjustment being rendered
45 permanent by means of the lock-nuts e⁴. This work of adjustment should be done by one person specially trained, and the final re-
sults obtained in this way are astonishing, even to those who have been accustomed to
50 consider the "solid-back" transmitter a sen-
sitive and powerful instrument. I ascribe these results to my use of a very thin metal auxiliary diaphragm, preferably of aluminum, and an adjustable rear electrode. As a
55 general rule I also make the body and stem of the front electrode, together with the clamp-
ing-nut g, of aluminum, and I consider this also an important part of the invention, al-
though I do not wish to be limited to the use
60 of this metal exclusively, as some other

metals for both the diaphragm and electrode give very good results.

While I have described my invention specifically and indicated the best form in which I have so far embodied it, sundry variations 65 will doubtless occur to those who are skilled in the art, and I therefore wish to state ex-
plicity that I am not confined to the specific forms and materials shown and described or even to the specific arrangement of parts, my 70 invention in its broadest aspect comprehend-
ing the combination I have indicated.

Having thus described my invention, what I claim, and desire to secure by Letters Patent of the United States, is—

75

1. In a telephone-transmitter, the combi-
nation with a casing, of a frame mounted in
said casing, a cup containing a resistance-
chamber adjustably mounted in said frame,
an electrode adjustably mounted in said cup, 80
insulating means within the cup, an auxiliary diaphragm mounted on said insulating
means, another electrode mounted on said
diaphragm, a main diaphragm connected to
said last-named electrode, and granular ma- 85
terial between said electrodes.

2. In a telephone-transmitter, the combi-
nation with a casing, of a frame mounted in
said casing, a cup containing a resistance-
chamber, a shank connected to said cup and 90
adjustably mounted in said frame, an elec-
trode in said cup provided with a shaft pass-
ing through an aperture in said shank and
adjustably connected thereto, insulating
means in said cup, an auxiliary diaphragm 95
carried by said insulating means, an elec-
trode supported on said auxiliary dia-
phragm, a shaft on said electrode, a main dia-
phragm connected to said shaft so that when
actuated it will convey the vibrations to said 100
auxiliary diaphragm, and granular material
between the electrodes in the cup.

3. A resistance - button for telephone-
transmitters comprising a supporting-shank
and cup integral therewith, an insulating-
ring within said cup and provided with 105
a threaded shoulder, a supplemental dia-
phragm resting upon said insulating-ring,
means for clamping the diaphragm in posi-
tion upon the insulating-ring, said means 110
also connected to the cup, an electrode sup-
ported by said supplemental diaphragm, and
granular material in the cup.

In witness whereof I have hereunto set my
hand 6th day of February, A. D. 1903, in the 115
presence of two subscribing witnesses.
